CLAIM

The ornamental design for a wrench-shaped vessel, as shown and described.

DESCRIPTION

FIG. 1 is a perspective view of a wrench-shaped vessel showing my new design;

FIG. 2 is a front elevational view thereof, the rear view being a mirror image of the front;

FIG. 3 is a right side view of the wrench-shaped vessel of FIG. 1;

FIG. 4 is a top view of the wrench-shaped vessel of FIG. 1; and,

FIG. 5 is a bottom view of the wrench-shaped vessel of FIG. 1.
